COMBINED BACKSPLASHER AND TOP FOR ELECTRIC RANGES

Richard Bolton Janes, Baldwin Lake, Mich., assignor to Gibson Refrigerator Company, Greenville, Mich., a corporation of Michigan

Application August 19, 1950, Serial No. 11,842

Term of patent 14 years

(Cl. D81—25)

To all whom it may concern:

Be it known that I, Richard Bolton Janes, a citizen of the United States, residing at Baldwin Lake, Greenville, in the county of Montcalm and State of Michigan, have invented a new, original, and ornamental Design for a Combined Back-splasher and Top for Electric Ranges, of which the following is a specification, reference being had to the accompanying drawing, forming a part hereof.

In the drawing:

Figure 1 is a perspective view of a combined backsplasher and top for electric ranges showing my new design, the end not shown being the same as the end shown, and the back is plain; and

Figure 2 is a cross-sectional view taken on substantially the line 2—2 of Figure 1.

The dominant features of my design reside in the portion shown in full lines.

I claim:

The ornamental design for a combined backsplasher and top for electric ranges, as shown and described.

RICHARD BOLTON JANES.
